CLAIM

The ornamental design for a weeding tool, as shown and described.

DESCRIPTION

FIG. 1 is a front view of a weeding tool showing my new design, a rear view being identical;

FIG. 2 is a left side view of the weeding tool, a right side view being identical;

FIG. 3 is a top view of the weeding tool;

FIG. 4 is a bottom view of the weeding tool;

FIG. 5 is a top front side perspective view of the weeding tool; and,

FIG. 6 is a bottom rear side perspective view of the weeding tool.
